UNITED STATES PATENT OFFICE.

SYVERT A. HESLA, OF BUTLER, MINNESOTA.

SUPPORT.

1,109,987.

Specification of Letters Patent.

Patented Sept. 8, 1914.

Application filed October 9, 1911. Serial No. 653,571.

To all whom it may concern:

Be it known that I, SYVERT A. HESLA, a citizen of the United States, residing at Butler, in the county of Ottertail, State of Minnesota, have invented certain new and useful Improvements in Supports; and I do hereby declare the following to be a full, clear and exact description of the invention, such as will enable others skilled in the art 10 to which it appertains to make and use the same.

This invention relates to supports and more especially to a maternity support and the primary object of the invention is to 15 provide an improved arrangement of webbing and connecting members whereby the support may be properly adjusted to suit various requirements and which will properly support all parts of the body in any 20 way affected, in the best possible position for health and comfort.

Another object of the invention is to provide a supporter which is provided with a novel arrangement of webbing forming the 25 same and combined in a novel manner with stocking supporters as well as proving readily adjustable, light, strong and not bungling, burdensome, oppressive or clumsy when worn outside the underwear.

With the above and other objects in view the invention consists of certain other combinations and arrangements of parts as will be hereinafter more fully described and claimed, it being a still further object of 35 the invention to provide a device which will not be likely to get out of working order.

In the drawings:—Figure 1 is a perspective view of the device as worn. Fig. 2 is a back view, also showing the device as 40 worn. Fig. 3 is an enlarged detail face view of an upper back connecting member used with the device with portions of the webbing engaged therethrough. Fig. 4 is a similar view of the lower connecting member. Fig. 5 is a detail front elevation of the 45 lower portion of the abdominal supporting portion and a stocking supporter connected therewith. Fig. 6 is a detail perspective view of a buckle mounted on each extremity of the main webbing. Fig. 7 is a similar 50 view of one of the buckles adapted to connect the abdominal supporting section of the webbing therewith. Fig. 8 is a perspective view of one of the buckles for the stocking supports.

Referring to the drawings in detail, there

is shown my improved supporter which comprises a main section of webbing 10 which extends around the back and beneath the arms and it is snugly engaged through a pair of spaced slots 11 in a trapezoidal plate 12, the said slots 11 being vertically convergent toward the upper end of the plate and lying parallel with the side edges of the plate so as to permit proper bowing of the webbing to conform to the positions of the back in use. The webbing is then extended upwardly in front of the arms and over the shoulders and in close proximity to the neck as shown at 13 and then extended downwardly through oppositely disposed pairs of slots 14 in an oval plate 15 located at the pit of the back between the arms, the said slots converging in opposite directions and being slightly spaced apart to bring the intermediate portions of the webbing in the same relation and from which point they extend downwardly and cross each other as shown at 16, where they are inserted inwardly through a slot 17 transversely of the trapezoidal plate 12 and then outwardly through a similarly disposed and longer slot 18 therebeneath and which is provided upon its lower edge with upwardly extending teeth 19 adapted to prevent downward movement of the webbing sections therethrough. The webbing sections are then inserted inwardly through a slot 20 also disposed transversely of the plate and spaced below the slot 18 where the webs are held from upward movement by means of inwardly and downwardly directed teeth 21 formed upon the lower edge of the slot 20 and the extremities of the webbing are then extended downwardly and around the 95 waist and below the abdomen.

Buckles 22 are slidably and adjustably mounted upon the extremities of the main web section 10 and comprise wire frames 23 having curved lower portions 24 and rearwardly offset vertical portions 25 which are engaged by turned ends 26 of a plate 27 at the rear portion of the frame. A front plate 28 is provided at its upper end with spaced ears 29 pivotally engaged with the horizontal portions of the wire frame and provided with intermediate teeth 30 disposed at right angles to the plate so that when the plate is moved to a closed position toward the frame, the said teeth will engage or bite into the 105 webbing and retain the same for movement and it will be seen that the lower portion of

- the plate is also circular in contour and is slightly spaced from the similar shaped portion of the frame for a purpose to be herein-after made apparent. Connected between 5 the buckle members 22 for adjustment is a webbing section 31 which has its extremities adjustably engaged in buckle members 32 which comprise rectangular wire frames 33 upon which is mounted an outer plate 34 through the medium of turned ends 35, the 10 said plate having its inner edge portion projecting beyond one side of the frame as shown and to this portion of the frame is attached a plate member 36 which is provided 15 with similar teeth as the plate member described in connection with the buckles 22 so that when the said plate member 36 is moved against the frame, the teeth will engage the webbing and hold the same from movement. 20 Mounted upon the opposite side of the frame relative to the plate 36 is a hook 37 constructed of a metal plate having an enlarged portion attached to the wire frame and provided with a bur stamped rearwardly there- 25 from at the curved portion of the hook so as to hold the parts in a flat position when in use, it being understood that all of the metallic parts are provided with rounded edges and constructed of such material as will not 30 corrode or affect the clothing of the wearer. The extreme ends of the section of webbing 10 are each provided with stocking engaging members 38 and for this purpose, buckles 39 are provided and comprise rec- 35 tangular wire frames 40 having a plate member 41 pivoted thereon and formed with teeth 41' in a similar manner as the plate members heretofore described except that the same is provided with a longitudinal 40 slot 42 through which the webbing section of the engaging members 38 is extended after being passed between the wire frame and a plate 43 attached to the front portion thereof while the free extremity of the plate 41 is 45 provided with a toothed edge 44 directed at

right angles toward the frame so as to engage the outer section of the webbing forming the engaging members and holding the same against movement when adjusted in the proper position.

50

From the foregoing description in connection with the accompanying drawings, it will be seen that a simple and efficient form of device is provided for the purposes set forth and it will be apparent that the device 55 will be further especially efficient owing to the fact that the use of the stocking supporters will serve to counterbalance the strain upon the shoulder engaging portion so as to keep the back erect and the chest forward 60 whereby each part of the device will exercise its duty in a pleasant and effective manner and permit free action of the limbs.

60

I claim:—

The combination with a single length of 65 webbing having a portion arranged to pass across the back of the wearer below the shoulders, said webbing being continued in front of the shoulders of the wearer and ex- 70 tends backward therefrom and down the wearer's back, the downwardly extending portions being crossed and having their ends brought around the wearer's body and continued in front thereof; of an abdomen-sup- 75 porting cross strap connecting the two ends of the webbing, a slide securing the downwardly extending portions of the webbing together between the wearer's shoulders, and a second slide below the last mentioned slide and se- 80 curing said downwardly extending portions at their crossing point and to the center of the first mentioned portion of the webbing, said slides being adjustable to and from each other.

In testimony whereof, I affix my signa- 85 ture, in presence of two witnesses.

SYVERT A. HESLA.
